ATTORNEY.

UNITED STATES PATENT OFFICE.

FREDERICK E. KOHLER, OF CANTON, OHIO.

DESIGN FOR A LAWN-RAKE.

SPECIFICATION forming part of Design No. 26,246, dated November 3, 1896.

Application filed August 12, 1896. Serial No. 602,580. Term of patent 3½ years.

To all whom it may concern:

Be it known that I, FREDERICK E. KOHLER, of Canton, Stark county, Ohio, have invented and produced a certain new and useful Design for Lawn-Rakes; and I do hereby declare the following to be a full, clear, and exact description of the design, such as will enable others skilled in the art to which it pertains to make and use the same.

My invention relates to a design for lawn-rakes; and it consists in the peculiar features which will be hereinafter fully set forth and claimed.

In the accompanying drawings, Figure 1 illustrates my design in perspective. Fig. 2 is a view in cross-section, taken on line $x x$, Fig. 1.

My design consists of a longitudinal bar A, which is composed of parallel upper and lower sides B C and a front side D, which is flat and at right angles to the upper and lower sides. This flat side D is located at the front of the rake, the rear side being open, as shown at E.

F represents a series of U-shaped curved teeth, which are curved transversely of the bar and visible between the sides B and C.

G illustrates a tubular extension connected with the bar A, and H illustrates a handle extending from said tubular extension.

The leading feature of my design is a head or cross-bar having parallel upper and lower sides and flat front side at right angles to the upper and lower sides and curved U-shaped teeth passing through the upper and lower sides.

What I claim is—

The design for lawn-rakes, as herein shown and described.

In testimony whereof I sign this specification, in the presence of two witnesses, this 4th day of August, 1896.

FREDERICK E. KOHLER.

Witnesses:

D. M. WILSON,
SAMUEL BURGERT.
